UNITED STATES PATENT OFFICE.

SWAYNE W. WILLIAMS, OF EAST ORANGE, NEW JERSEY.

PUMP.

1,169,707.

Specification of Letters Patent. Patented Jan. 25, 1916.

Application filed November 14, 1914. Serial No. 872,121.

To all whom it may concern:

Be it known that I, SWAYNE W. WILLIAMS, a citizen of the United States, residing at East Orange, Essex county, in the 5 State of New Jersey, have invented certain new and useful Improvements in Pumps, of which the following is a full, clear, and exact specification.

My invention relates to improvements in 10 pumps, and the same has for its object more particularly to provide a simple, efficient and reliable pump adapted to be operated by a foot pressure, by means of which the fluid may be initially compressed in a large 15 cylinder, and thence further compressed within a small cylinder, and thence discharged therefrom.

Further, said invention has for its object 20 to provide a duplex pump comprising a pair of connected cylinders and pistons working within said cylinders, which pistons are adapted to be alternately depressed and elevated by shifting of the weight of the person standing thereon.

Further, said invention has for its object 25 to provide a pump comprising a plurality of connected cylinders within which are disposed rigid piston members and movable cylinder members surrounding said fixed piston members, provided at their inner 30 ends with heads serving as pistons for said connected cylinders.

Further, said invention has for its object 35 to provide a duplex pump in which the air is alternately initially compressed in a cylinder of large area, and thence conducted into a smaller cylinder, and further compressed therein, and thence discharged 40 therefrom and through the outlet of the pump.

To the attainment of the aforesaid objects and ends, my invention consists in the novel details of construction, and in the combination, connection and arrangement of 45 parts hereinafter more fully described and then pointed out in the claims.

In the accompanying drawings wherein like numerals of reference indicate like parts,—Figure 1 is a side view showing one 50 form of pump constructed according to and embodying my said invention; Fig. 2 is a central longitudinal section thereof; Fig. 3 is an end view, and Figs. 4 and 5 are detail 55 central sectional views showing the construction and arrangement of the intake and

discharge valves located in the fixed piston members of the pump.

In said drawings 10 designates the pump as a whole comprising a base 11, and main cylinders 12, 12' arranged side by side and 60 preferably formed integrally with said base 11. Within each of said main cylinders 12, 12' are centrally disposed uprights or fixed piston rods 13, 13' which are provided at 65 their upper ends with heads 14, 14', respectively. The said heads 14, 14' are provided with screw threads adapted to engage with corresponding threads arranged upon the upper ends of said uprights or fixed pistons. Within the casings 12, 12' are located large 70 piston heads 15, 15' which are secured upon the lower ends of hollow pistons 16, 16' extending through suitable openings provided in the tops 17, 17' of the casings 12, 12', respectively. The hollow pistons 16, 16' 75 which serve as secondary compression chambers are provided at their upper projecting ends with heads 18, 18' serving as supports for the feet of the operator.

The cylinders 12, 12' are provided adjacent to their lower ends with intake openings 19, 19', provided with check valves 20, 20'. Intermediate said cylinders 12, 12' are located vertical supports or standards 21, 80 upon the upper ends of which are pivotally mounted levers 22, 22 having their opposite ends connected to links 23, 23', pivotally secured at their upper ends to lugs 24, 24' extending from the opposite sides of the heads 18, 18', of the hollow pistons or secondary 85 cylinders 16, 16'.

Intermediate the cylinders 12, 12' is secured a discharge nipple 25 which communicates with a horizontal passage 26 provided in the base 11. One end of said passage 26 90 95 communicates with a vertical passage 26^a provided in the upright or fixed piston rod 13, and is provided at its upper end with an outlet opening 26^c controlled by an outlet check valve 27^a, while the opposite end of 100 said horizontal passage 26 communicates with a vertical passage 26^b provided in the fixed piston 13' of the cylinder 12'. The upright or fixed piston 13' is provided at its 105 upper end with an outlet opening 26^d controlled by a check valve 27^b.

28 denotes a horizontal passage provided in the base 11, communicating at one end with a vertical passage 28^a provided in the upright or fixed piston 13. The upper end 110

of said passage 28^a is provided with an inlet opening 28^b controlled by a check valve 29^a, while the opposite end of said horizontal passage 28 is provided with an outlet 28^c opening into the base of the casing 12'.
5

30 denotes a horizontal passage provided in the base 11 having one end communicating with a vertical passage 30^b provided in the fixed piston 13'. The upper end of said 10 passage 30^b is provided with an inlet opening 30^c controlled by a check valve 31^b while the opposite end of said horizontal passage 30 is provided with an outlet opening 30^a which communicates with the interior of the 15 cylinder 12.

The outlet valves 27^a, 27^b in the pistons 13, 13' each comprise a horizontal partition 35 having a passage 36 therein, and a spring 37 disposed above said partition 35 serving 20 to hold a ball valve 38 spring pressed against a removable seat 39 which has its edge in screw-threaded engagement with the upper end of said upright or fixed piston, and bearing against a shoulder 40 provided 25 on said fixed piston.

The inlet valves 29^a, 31^b, in the fixed pistons 13, 13' each comprise an inclined valve seat 41 upon which is seated a ball valve 42, held in spring pressed engagement with its 30 seat by a spring 43 secured in place by an adjustable bearing member 44 maintained in screw-threaded engagement with the outer end of said fixed piston.

The operation of my improved pump is 35 as follows:—In order to operate the pump, it merely becomes necessary for the operator to stand on the heads 18, 18' of the pump and thence, by shifting his weight from one foot to the other, cause the movable pistons 16, 16' to be alternately depressed and elevated. As the hollow piston 16 is initially depressed it will cause the air within 40 the cylinder 12 to be compressed by the action of the descending piston 15 and force the air from said cylinder 12 through the 45 outlet 30^a, horizontal passage 30, vertical passage 30^b, through the inlet valve 31^b and inlet opening 30^c into the hollow piston 16'.
With the shifting of the weight of the operator to the hollow piston 16' the air contained within said hollow piston 16' above the head 14' therein will be compressed within 50 said hollow piston, and forced into the outlet valve 27^b, through the vertical passage 26^b, passage 26, and discharged through the outlet nipple 25. As the hollow piston 16' is descending the head 15' thereof will cause the air contained within 55 said cylinder 12' to be compressed therein, and forced through the opening 28^c, horizontal passage 28, vertical passage 28^a, in the fixed piston 13, and forced through the inlet valve 29^a and inlet 28^b therein and into the portion of the hollow piston 16 above 60 the head 14 therein, whence the air will be

forced, by the succeeding depression of the piston 16, through the outlet opening 27^a, vertical passage 26^a, in the fixed piston 13, horizontal passage 26, and be discharged through the nipple 25.
70

Having thus described my said invention, what I claim and desire to secure by Letters Patent is:—

1. A pump comprising a pair of main casings, each having a movable piston working therein, a hollow stem for each of said pistons forming a secondary casing, fixed pistons in said main casings extending into said secondary casings, and means for conducting the initially compressed fluid from each of said main casings to the other of said secondary casings for further compression therein and discharge therefrom, substantially as specified.
75

2. A pump comprising a pair of main casings, each having a movable piston working therein, hollow stems for each of said pistons forming secondary casings of smaller area than said main casings, fixed pistons in said main casings extending into said secondary casings, and means for conducting the initially compressed fluid from one of said main casings to the other of said secondary casings for further compression therein and discharge therefrom, substantially as specified.
80

3. A pump comprising a pair of main casings, each having a movable piston therein, a hollow stem for each of said pistons forming a secondary casing, fixed pistons mounted in said main casings and extending into said secondary casings, and means for alternately conducting the initially compressed fluid from one of said main casings to the other of said hollow stems forming said secondary casings for further compression therein and discharge therefrom, substantially as specified.
85

4. A pump comprising a base, a pair of main casings mounted thereon, a discharge outlet for said casings, a hollow, movable piston arranged to work in each of said main casings and forming a secondary casing, fixed pistons centrally secured within said main casings and extending upwardly from the base thereof and into said hollow pistons; said fixed pistons having outlets therein communicating with each other and with said discharge outlet, and said main casings having outlets therein each communicating with the interior of the other of said hollow pistons, and valve means provided in said fixed pistons for controlling the passage of fluid from each of said main casings to the other of said secondary casings, substantially as specified.
100

5. A pump comprising a base, a pair of main casings, each having a movable piston therein, a hollow stem for each of said pistons forming a secondary casing, fixed pis-

- tons mounted in said main casings and extending into said secondary pistons, a support arranged upon said base intermediate said main cylinders, a member pivotally mounted upon said support having its opposite ends pivotally secured to the hollow stems of said pistons, and means for alternately conducting the initially compressed fluid from one of said main casings to the other of said hollow stems forming said secondary casings for further compression therein and discharge therefrom, substantially as specified. 35
6. A pump comprising a base, a pair of main casings mounted upon said base, a discharge outlet for said main casings, a hollow movable piston arranged to work in each of said main casings and forming a secondary casing, fixed pistons secured at their lower ends to said base, within said main casings, and extending upwardly therefrom into said secondary casings; said fixed pistons having outlets therein communicating with each other and with said discharge outlet, and said main casings having outlets therein each communicating with the interior of the other of said hollow pistons, valve means provided in said fixed pistons for controlling the passage of fluid from each of said main casings to the other of said secondary casings, a support, a lever pivotally mounted upon said support and links pivotally secured to the ends of said lever, and to said hollow movable pistons, substantially as specified. 40
7. A pump comprising a base, a pair of main casings mounted upon said base, a discharge outlet for said main casings, a hollow movable piston arranged to work in each of said main casings and forming a secondary casing, fixed pistons secured at their lower ends to said base, within said main casings, and extending upwardly therefrom into said secondary casings; said fixed pistons each having an outlet and a passage extending therefrom to the other of said main casings, and an outlet connected by a common passage communicating with said discharge outlet, and valve means provided in said inlets and outlets, a pair of supports secured upon said base, levers pivotally mounted upon said supports, and links connecting the ends of said levers with the outer projecting ends of said hollow movable pistons, substantially as specified. 45
